UNITED STATES PATENT OFFICE.

WILLIAM SPENCER PURSER, OF PALMERS GREEN, LONDON, ENGLAND, ASSIGNEE TO
COLUMBIA GRAPHOPHONE COMPANY, LIMITED, OF LONDON, ENGLAND.

MOVING-COIL ELECTRICAL INSTRUMENT.

Application filed February 11, 1926, Serial No. 87,727, and in Great Britain December 16, 1924.

This invention relates to sound recorders, sound amplifying devices or loud speakers and microphones of the kind involving a moving coil system.

5 The object of the present invention is to devise improvements in the construction and arrangement of apparatus of the above character which will increase their sensitivity, and the invention consists in sound recorders, sound-amplifying devices and microphones of the kind referred to embodying a plane or flat coil which may be mounted between two adjacent plane or flat parallel magnet pole pieces so that the plane of the 10 coil is parallel to the faces of said pole pieces.

The invention also consists in apparatus of the above character in which the coil is formed as a flat spiral.

20 The invention further consists in apparatus of the above character in which substantially only one-half the coil is situated in the magnetic field.

The invention also consists in the apparatus hereinafter described or indicated.

The accompanying drawings illustrate two modes of carrying out the invention.

Figure 1 is an elevation of one form of apparatus in accordance with the invention; 30 Figure 2 is a side elevation, and

Figure 3 is an underneath plan of a part of the apparatus shown in Figure 1;

Figure 4 is a perspective view of a modified form of apparatus in accordance with 35 the invention;

Figure 5 is an elevation of the coil shown in Figure 4, and

Figure 6 is a view showing the invention applied to a microphone.

40 In carrying my invention into effect in one convenient manner as, for example, in its application to a sound-amplifying device or so-called loud speaker as employed in connection with wireless telephony, and as

45 illustrated in Figures 1 to 3, I attach to the diaphragm *a* of the loud speaker a flat coil *b* in the form of a flat spiral, the coil, which carries the incoming telephone currents, being mounted at right angles to the dia-

50 phragm and to the magnetic field produced by the electromagnet *c* of the loud speaker and being free to move in and out between the pole pieces of such electromagnet.

The magnet poles *d* are rectangular in

shape with or without rounded edges and are 55 separated by a distance which is just sufficient to allow the flat coil to clear each of the adjacent flat parallel pole faces, the advantage of such an arrangement being that it is possible to considerably reduce the total 60 space between the poles, thus increasing the strength of the magnetic field and the sensitivity of the instrument. Another advantage of the small gap is that the spaces may be filled with sponge rubber or with oil or 65 other liquid which, owing to the small dimensions of the gap, will be held in place by capillary attraction without the necessity for any container. Moreover, the air gap may be readily adjusted if desired. 70 One-half of the flat coil is situated within the magnetic field.

The flat thin spiral constituting the layer of the coil may consist of fine insulated wire which may comprise any number of turns 75 from the center to the outside edge, the number of turns and diameter of the wire used being determined by the area of the pole pieces and the electrical or other characteristics of the instruments to which the invention is applied.

The spiral may have retaining sides of mica or other thin rigid substance and the whole be impregnated with paraffin wax or insulating varnish, or the coil may be impregnated with some substance to give it 85 rigidity and be used without retaining sides or other support for the wires.

A further method according to the invention is shown in Figures 4 and 5 where the 90 coil is wound as a single twisted spiral, shaped somewhat as the figure 8, each flattened end being placed in a magnetic field while the central portion may be used as the means of suspension or point of attachment to its instrument.

The invention may similarly be applied to electrical sound recording devices and to microphones.

Figure 6 shows the application of the invention to a microphone, the arrangement being similar to that shown in Figure 1 with the exception that the diaphragm *a* is omitted and a pad or mounting *a'* of sponge rubber or the like provided for the support 100 of the coil. In this modification a diaphragm need not be employed and is omitted 105 as shown in the drawing.

Having now described my invention what I claim as new and desire to secure by Letters Patent is:—

1. In a telephonic instrument, a pair of magnet poles placed close together, a substantially rigid plane coil between said poles, said coil having its plane substantially perpendicular to the field of said poles, and a resilient support for said core, said coil

being adapted to act directly in the electro-acoustic transfer of energy.

2. In a telephonic instrument, a pair of magnet poles placed close together, a substantially rigid coil between said poles, and a block of soft rubber supporting said coil, is

In testimony whereof I have signed my name to this specification.

WILLIAM SPENCER PURSER.
